US00D800702S

(12) **United States Design Patent** (10) Patent No.: **US D800,702 S**
Muller (45) Date of Patent: **** Oct. 24, 2017**

(54) **WIRELESS REMOTE-CONTROL APPARATUS**

(71) Applicant: **MU DESIGN SARL**, Esch-sur-Alzette (LU)

(72) Inventor: **Vivien Muller**, Metz (FR)

(**) Term: **15 Years**

(21) Appl. No.: **35/501,181**

(22) Filed: **Jun. 20, 2016**

(80) **Hague Agreement Data**

Int. Filing Date: **Jun. 20, 2016**

Int. Reg. No.: **DM/091242**

Int. Reg. Date: **Jun. 20, 2016**

Int. Reg. Pub. Date: **Jul. 8, 2016**

(51) **LOC (10) Cl.** **14-03**

(52) **U.S. Cl.**

USPC **D14/218**
